HENRY PLETSCH, OF CHICAGO, ILLINOIS, ASSIGNOR TO JUDD LAUNDRY MACHINE COMPANY, OF WILMINGTON, DELAWARE, A CORPORATION OF DELAWARE.

ACTUATING MECHANISM.

1,113,686.

Specification of Letters Patent.

Patented Oct. 13, 1914.

Application filed November 22, 1912. Serial No. 732,963.

To all whom it may concern:

Be it known that I, HENRY PLETSCH, a citizen of the United States, residing at Chicago, in the county of Cook and State of Illinois, have invented a certain new and useful Improvement in Actuating-Mechanism, of which the following is a specification.

My invention relates to actuating mechanism, and the object of the invention is to provide mechanism whereby a pivotally supported body may be oscillated back and forth upon a supporting pivot and the direction of motion changed rapidly without shock or jar to the machine.

I have chosen to illustrate the invention as applied to a washing machine, and in this form the tub constitutes the oscillating body.

20 I accomplish my object by the mechanism illustrated in the accompanying drawings, in which—

Figure 1 is a general side elevation of the machine. Fig. 2 is a plan view of the operating parts thereof, and Fig. 3 is a detail section taken vertically through the supporting axis of the tub.

In the several views similar numerals denote like parts.

30 The tub 1 is supported upon a frame comprising side beams 2 and cross beams 3 supported upon legs 4 and provided with braces 5. Projecting outward from each side of the tub is a pin 6 which bears in a casting 7 mounted on the adjacent side beam 2. The pins and their supports, therefore, constitute trunnions by which the tub is pivotally supported upon the frame. On one side of the frame two pins 10 are located on opposite sides of the tub pivot 6. By preference these pins are supported by suitable extensions of the casting 7. Rocker arms 11 are pivotally supported upon said pins 10 and are articulately connected at their upper ends to a link 12. Between the ends of this link is a pin 13, which is connected both to a connecting rod 14 and the lower end of an actuating spring 15. The upper end of spring 15 is connected to the tub, preferably at or near the upper edge thereof. In the preferred design the upper end of the spring is attached to branches 16 of a casting secured to the side of the tub and extending down to and formed integral with a hub 17 which holds the pin 6, above mentioned.

Rod 14 is connected to a crank 18 driven by a shaft 19 supported upon a bracket 20 carried by the frame of the machine.

Auxiliary springs 25 and 26 are attached to the tub preferably near the bottom thereof, where bosses 27 form extensions of the casting 16—17. Said auxiliary springs extend diagonally downward and outward from the tub, their lower ends being attached to a part of the frame-work, preferably the lower ends of the legs 4.

During the operation of the machine, when the crank 18 is rotated, the connecting rod 14 moves back and forth and produces a corresponding movement in the link 12 and lower end of the spring 15. This motion causes the body to be oscillated, first in one direction and then in the opposite direction about the pivots 6. The springs 25 and 26 serve alternately to assist the spring 15 in reversing the direction of motion of said body. As the reversal is thus accomplished solely by means of springs the machine operates very smoothly, without shock of any kind.

Having thus described my invention, what I claim as new, and desire to secure by Letters Patent, is:

1. In combination, a stationary frame, an oscillating body pivoted thereto, a pair of rocker arms whose axes of rotation are remote from the axis of oscillation of said body, said arms being pivoted to said frame, a connecting rod, a spring connected at one end to said rod and at the other end to said body, said connecting rod being connected to said rocker arms and having its movement in part controlled by said rocker arms, and means for actuating said connecting rod.

2. In combination, a stationary frame, a pivotally supported body mounted thereon, a pair of pivotally supported rocker arms whose pivots are remote from the pivot of said body, said arms being pivoted to said frame, a link connecting the free ends of said rocker arms, means for rocking said arms and supporting link back and forth, and a spring connected at one end to said link and at the other end to said body.

3. In combination, a stationary frame, an oscillating body pivoted thereon, a pair of rocker arms articulately supported upon said frame at points remote from the axis of oscillation of said body, means for rock-

- ing said arms, a link connecting the free ends of said rocker arms, and a spring connected at one end to said link and at the other end to said oscillating body.
- 5 4. In combination, a stationary frame, an oscillating body pivoted thereto, a pair of rocker arms whose axes of rotation are remote from the axis of oscillation of said body, said arms being pivoted to said frame, 10 a connecting rod, a spring connected at one end to said rod and at the other end to said body, said connecting rod being connected to said rocker arms at the free ends thereof and having its movement in part controlled 15 by said rocker arms, means for actuating said connecting rod, and auxiliary springs for coöperating with the first mentioned spring to reverse the direction of oscillation of said oscillating body.
- 20 5. In combination, a stationary frame, an oscillating body pivotally supported thereon, a pair of rocker arms pivotally attached to said frame at points remote from and on opposite sides of the axis of oscillation of said body, a link connecting the free ends of said arm, an actuating spring connected at one end to said link and at the other end to the upper part of said body, a connecting rod and means for actuating the same, said 25 connecting rod being connected to the lower end of said spring and to said link, and auxiliary springs extending obliquely downward from said body in opposite directions, the lower ends of said auxiliary springs being attached to the lower part of said stationary frame.
6. In a machine of the class described, the combination of a stationary frame, an oscillating body pivoted thereon and rotatable about a horizontal axis, a movable element, a 40 spring connecting said movable element and said body for actuating the latter, and supporting means upon the frame for supporting said movable element, said supporting means permitting both vertical and longitudinal movement of said movable element and maintaining it always horizontal. 45
7. In a machine of the class described, the combination of a stationary frame, an oscillating body pivoted thereon and rotatable about a horizontal axis, said axis being below the center of gravity of said body, means for yieldingly holding the body upright with its center of gravity above the pivotal point of support, a movable element, 50 a spring connected to said movable element and said body for actuating the latter, pivoted arms mounted on the frame on opposite sides of the axis of oscillation of the body, said arms supporting said movable element and permitting it to move longitudinally and vertically and causing it at all times to maintain a position of horizontality, and means for actuating said movable element. 55
- In witness whereof, I have hereunto subscribed my name in the presence of two witnesses.
- HENRY PLETSCH.
